A. F. JENKINS.

OXYACETYLENE TORCH.

APPLICATION FILED OCT. 13, 1913.

1,228,676.

Patented June 5, 1917.

UNITED STATES PATENT OFFICE.

ALEXANDER F. JENKINS, OF BALTIMORE, MARYLAND, ASSIGNOR TO THE ALEXANDER MILBURN COMPANY, OF BALTIMORE, MARYLAND, A CORPORATION OF MARYLAND.

OXYACETYLENE-TORCH.

1,228,676.

Specification of Letters Patent.

Patented June 5, 1917.

Application filed October 13, 1913. Serial No. 794,338.

To all whom it may concern:

Be it known that I, ALEXANDER F. JENKINS, a citizen of the United States of America, and resident of Baltimore, Maryland, have invented certain new and useful Improvements in Oxyacetylene-Torches, of which the following is a specification.

This invention relates to improvements in torches for use in connection with oxy-acetylene generating or other apparatus adapted to supply a suitable combustible mixture capable of developing the intense heat necessary for welding metals and for similar purposes.

15 One of the principal objects of the invention is to construct a light hand operable tool with a simple arrangement of parts to form a suitable handle section provided with gas passageways, the controlling means of 20 which may be readily adjusted by the hand holding the torch.

A further object comprises the arrangement of the valve stems and operating means therefor so that both will be confined within 25 the general outline of the handle section of the torch so that they will not accidentally catch in the clothing of the operator or elsewhere.

Another object of the invention is to provide a torch in which the gases forming the combustible mixture are intimately mixed so that the danger from back-firing and explosion will be eliminated.

The above and other objects and the novel 35 features of the invention will be apparent from the following description, taken in connection with the drawings, in which—

Figure 1 is a side elevation of a torch embodying my invention;

40 Fig. 2 is a vertical longitudinal section of the rear casting of the handle section;

Fig. 3 is a vertical longitudinal section of the front casting of the handle section;

Fig. 4 is a central vertical section of the 45 torch head;

Fig. 5 is a cross-section along the line 5—5 of Fig. 1, looking in the direction of the arrows, and

Fig. 6 is a transverse cross section on the 50 line 6—6 of Fig. 4.

Referring to the drawing, the torch comprises a handle section, a head or burner section, and a tube connecting the head with the handle section. The handle section com-

prises two castings which are connected by 55 two or more pipes to form a grip in the shape of a frame, the gases forming the combustible mixture entering the pipes through passageways into the rear casting and discharging from said pipes in the front casting 60 where they unite in the mixing chamber flowing from thence through the connecting tube into the head and discharging at the tip of the latter.

A brass casting 10, for convenience designated the rear or inlet casting, is located at the rear of the handle section and provided with two inlet openings 11 and 12. Suitable hose couplings 13 and 14 are threaded to fit in the inlet openings 11 and 12 and are respectively connected by flexible hose or otherwise to oxygen and acetylene supplies under pressure.

An unobstructed oxygen passageway 15 extends from the inlet opening 11 through 75 the casting at its lower end and opens into the pipe connection 16. The inlet opening 12 communicates with an acetylene passageway 17 extending through the upper portion of the casting and is provided intermediate 80 its ends with a valve chamber 18 in which a needle valve 19 is arranged to control the flow of gas through the passageway 17 to the pipe connection 20. The needle valve 19 is formed integral with the end of a valve 85 stem 21 which extends through a boss 22 on the front side of the rear casting 10, a sleeve 23 serving to maintain the packing 24 around said valve stem 21 and prevent leakage past the stem.

A brass casting 25 designated for convenience the front casting has two inlet pipe connections 26 and 27 on its rear face. The metal pipes 28 and 29 are suitably threaded at their ends to fit the pipe connections 16, 95 26 and 20, 27 respectively, to thereby connect the two castings 10 and 25 and form a frame or handle section for the torch. The pipes 28 and 29 are arranged parallel to one another and form a suitable grip for the 100 tool.

The pipe connection 26 opens into a passageway 30 which extends upwardly in an inclined direction through the lower part of the front casting 25 to a valve chamber 31 in which the needle valve 32 operates. The needle valve 32 is formed integrally with the valve stem 33 which extends through a boss 105

34 on the rear face of the front casting 25 and packing 35 is held in place around said valve stem by means of a sleeve 36 to prevent leakage past the valve stem. The valve 32 5 controls the admission of oxygen from the chamber 31 to the passageway 37 which is in a sense a continuation of the passageway 30 and leads to a mixing chamber in the casting 38 fitted to the front end of the casting 25 by 10 the screw threaded connections 39.

15 The casting 38 in which the mixing chamber is formed has a tapering inlet opening 40. The inlet opening 40 is connected to a flaring outlet opening 41 by means of a narrow passageway 42, the outlet opening 41 discharging into the pipe connection 43 to which the connection mixture tube 44 is attached.

20 The pipe connection 27 leads to a passageway 45 which has a tapering portion 46 terminating in the passageway 47 of uniform section located in the discharge tip 48 which latter is disposed in the inlet 40 of the mixing chamber 38. An annular chamber is 25 thus formed around the tip 48 and a mixing device in the form of an injector is provided. The tip 48 forms the nozzle of the injector, an annular chamber 49 being provided into which the oxygen from the passageway 37 is 30 forced under pressure and drawn by the action of the injector. The injector serves to intimately mix the gases, the discharge outlet 47 of the tip 48 being concentrically arranged with the mixing chamber in the casting 38 and the acetylene therefrom meeting the oxygen from the passageway 37 as it enters the mixing chamber.

35 The mixture tube 44 is threaded at one end to fit the connection 43 and at its opposite end to fit the pipe connection 50 in the head casting 51, disposed at an angle thereto, delivering the mixture from the front casting to the burner head through a side opening 52 in the casting 51.

40 The head casting 51 has an opening in its upper end which opening is closed by means of the screw plug 53. Below the inlet opening 52 of the casting 51 there are two series of restricted circular passageways 55 arranged concentrically which connect a chamber 56 opposite the said inlet opening 52 with a chamber 57 near the lower end of the casting 51. At its center the plug 58 through which the passageways 55 extend is 45 solid. A detachable burner tip or nozzle 59 is secured to the casting 51 by means of a threaded sleeve 60 which has an inturned flange 61 that engages under a shoulder 62 on the burner tip. The burner tip has a central passageway 63 extending therethrough in line with the solid portion of the plug 58. The chambers 56 and 57 at opposite ends of the casting, together with the restricted passageways 55, serve to more thoroughly mix 55 the gases and prevent back-fire, the fact that,

the passageway 63 is also out of line with any of the restricted passageways 55 also serves to assist in mixing the gases and prevent back-firing or explosions.

55 It will be noted that the valve stems 21 and 33 are arranged in line and directed toward one another. Each valve stem is provided with a threaded portion 64 at its outer end which fits in sockets 65 at opposite ends of a knurled turn-buckle 66. The sockets 70 are interiorly threaded so that when the turn-buckle is rotated in one direction both valve stems will be withdrawn and permit the flow of gases through the passageways which they control and when turned in the opposite direction both valve stems may move in opposite directions to adjust the flow or cut it off as desired. The turn-buckle 66 is placed between the parallel pipes 28 and 29, and is of such a size that it will 85 not extend appreciably beyond the general outlines of the handle section and can be readily turned by the hand which holds the torch. The outer ends of the valve stems are each guided by means of a suitable hub 67 on a spider 68 which latter is located between the pipes 28 and 29. The turn-buckle 66 is prevented from moving longitudinally by the spiders 68 at the ends thereof against which said turn-buckle bears. 95

100 As shown in Figs. 1 and 5, intermediate the ends of each valve stem there is a corrugated ratchet device 69 which is rigidly mounted on the valve stem or may be made integral therewith. A metal band 70 is fitted around the pipes 28 and 29 opposite each ratchet member 69 and has projections 71 and 72 struck therefrom on opposite sides of said ratchet device, the said projections acting as pawls and engaging the ratchet wheel 105 69 and serving to prevent the accidental rotation of the valve stem and also to prevent its rotation when the turn-buckle or knob 66 is rotated. The pair of spiders 68 and the bands 70 serve as reinforcing elements for 110 the frame formed by the pipes 28 and 29. However, the pawl and ratchet devices which prevent the accidental rotation of the valve stem are so arranged that they will not prevent the independent adjustment of 115 one or the other of said valve stems as it is possible with sufficient turning effort to force the ratchet 69 past the projections 71 and 72 and effect the independent adjustment of either valve stem. A pin 73 projects from 120 each valve stem between the spider 68 and band 70 and serves to engage the hub 67 and limit movement of the valve stem into the socket 65 so that the valve stems will not jam therein. 125

125 The operation of the device will be clear from the foregoing description. Oxygen and acetylene being admitted at the inlets 11 and 12 will flow through the casting 10, pipes 28 and 29 into the front casting 25 130

where they will unite in the mixing chamber in the part 38 of the said casting flowing from thence as a mixture to the casting 51 of the head where they are more thoroughly 5 mixed and discharged through the passageway 63 in the tip 59. The supply of gases may be simultaneously regulated by means of the turn-buckle 66 to which the valve stems are attached. It will be seen that a 10 simple and handy appliance has been constructed which may be easily and safely manipulated and which is susceptible of numerous modifications. It is therefore not intended to limit the invention to the exact 15 details as shown and described.

Having thus described my invention, what I claim is:

1. In a torch of the class described, the combination of a casting having channels 20 extending therethrough, a second casting having channels therethrough, pipes connecting the castings and the channels therein thereby forming gas conduits, valves controlling said conduits, stems connected with 25 said valves, means for operating said stems and valves, the stems and operating means extending between the said pipes, and a torch head connected to one of said castings.

2. In a torch of the class described, the 30 combination of castings having passageways extending therethrough, pipes connecting the castings and the passageways therein, valves controlling said passageways and operating means for said valves 35 having parts thereof disposed between said pipes.

3. In a torch of the class described, the combination of a handle section comprising 40 a casting having gas inlets, a second casting having gas outlets, and pipes joining the castings and connecting the inlets with the outlets, means extending into the space between said pipes for controlling the flow of gas from said inlets to said 45 outlets, a burner tip, and a tube between and connecting the burner tip with the handle section.

4. In a torch of the class described, the 50 combination of a handle section comprising a casting at one end having inlets, one of which is provided with a valve, a casting at the opposite end having independent passageways therein, one of which is provided with a valve, and pipes connecting the passageways in the second casting with the passageways in the first casting, operating means for said valves, said means being located between the said pipes, a burner tip, and a pipe connecting the 55 burner tip with the second casting.

5. In a torch of the class described, the combination of a casting having passageways therethrough, a valve controlling one 60 of the passageways, a second casting having passageways therein, a second valve

controlling one of the last mentioned passageways, pipes connecting the two castings and the passageways therein, said valves having stems, the stems of the valves extending between the said pipes, a burner 70 tip, and a tube connecting the burner tip to said second casting.

6. In a torch of the class described, the combination of a plurality of pipes, means at the ends of the pipes connecting the same 75 to form a handle, means extending between the pipes for controlling the flow of gas through said pipes, a burner nozzle, and a tube disposed between the burner nozzle and the pipes.

7. In a torch of the class described, the combination of a plurality of pipes, means connecting corresponding ends of 80 said pipes, said means having fluid inlets one of which is controlled by a valve, a 85 nozzle constituting the burner of said torch, a mixture tube discharging into said nozzle, and means for connecting the outlet ends of said pipes to said tube comprising a member having mixing means therein and 90 a valve controlled passageway leading to said mixing means.

8. In a torch of the class described, the combination of a casting having an unobstructed passageway and a valve controlled 95 passageway, a second casting having an unobstructed passageway connected to said valved passageway in the first mentioned casting, and a valved passageway connected to the unobstructed passageway in the first 100 mentioned casting, said second casting also having a common outlet for the passageways therein, and a burner nozzle connected to said outlet.

9. In a torch of the class described, the 105 combination of parallel pipes, devices whereby said pipes are connected at their ends to form a grip for the torch, each of said devices having a valved passageway and an unobstructed passageway therein, 110 and a burner nozzle attached to one of said connecting devices.

10. In a torch of the class described, the combination of a plurality of pipes, members connecting said pipes at their ends, 115 said members having passageways therethrough opening into said pipes, a gas mixing device on one of said members, a valve located on the member upon which said mixing device is mounted, said valve controlling the supply of gas from one of said passageways to said mixing device, and a burner head connected to receive the mixture from said mixing device.

11. In a torch of the class described, the 125 combination of devices having passageways extending therethrough, pipes connecting the passageways in said devices, a burner head, a mixing device in one of said devices having one inlet thereof located di- 130

- rectly in line with one of said pipes, and means for controlling the flow of gas through said pipes to said mixing device.
12. In a torch of the class described, the combination of a front casting and a rear casting each having passageways therein, pipes connecting the passageways in the castings, an injector within the front casting to which both the passageways in the latter lead and a valve in said front passageway controlling the supply of gas from one of said passageways to said injector.
13. In a torch of the class described the combination of front and rear castings having passages therein, pipes between said castings connecting the same and the passages therein, a valve on each casting controlling a passage therein, means whereby said valves may be simultaneously operated and a burner head and tip connected to the front casting.
14. In a torch, the combination of castings having passageways therein, pipes connecting the passageways and castings, valves controlling the passageways, operating means for the valves disposed between said pipes, and a burner head connected to one of said castings.
15. In a torch, the combination of castings having passageways therein, pipes connecting the passageways and castings, valves controlling the passageways, and having valve stems extending between said pipes, means disposed between said pipes for operating the stems to adjust the valves and a burner head connected to one of said castings.
16. In a torch of the class described, the combination of front and rear castings having passages therein, oxygen and acetylene pipes connecting said castings and the passages therein, a valve on each casting controlling a passage therein, means whereby said valves may be adjusted independently of each other, and means whereby the valves may be simultaneously operated.
17. In a torch, the combination of castings having passageways extending therethrough, pipes connecting said castings and the passageways therein, a valve in each casting controlling one of the passageways therein, a common means for operating both valves, and a torch-head connected to one of said castings.
18. In a torch, the combination of castings having passageways extending therethrough, pipes connecting said castings and the passageways therein, a valve in each casting controlling one of the passageways therein, valve stems attached to the valves and extending between said pipes, a turnable device between the ends of the stems and adapted to engage and move the latter, and a torch head connected to one of said castings.
19. In a torch, the combination of castings having passageways extending therethrough, pipes connecting said castings and the passageways therein, a valve in each casting controlling one of the passageways therein, valve stems attached to the valves and extending between said pipes, a turnable device having threaded sockets adapted to receive the ends of the stems and move the same longitudinally, means for guiding the stems and preventing the rotation thereof, and a torch head mounted on one of said castings.
20. In a torch, the combination of castings having passageways extending therethrough, pipes connecting said castings and the passageways therein, a valve in each casting controlling one of the passageways therein, valve stems attached to the valves and extending between said pipes, said stems being threaded at their outer ends and provided with corrugations intermediate their ends, projections engaging said corrugated portions of the valve stems to prevent the accidental rotation of the stems but permitting the adjustment thereof at will, a turnable member provided with threaded sockets to receive the threaded ends of said stems, said member being adapted to move the stems longitudinally, guiding means for the stems and adapted to reinforce the pipes, and a torch head mounted on one of said castings.
21. A torch head comprising a casing having an inlet and an outlet and two mixing chambers between said inlet and outlet connected by a plurality of parallel contracted passageways.
22. A head for a torch of the class described, comprising the combination of a casing having an inlet, a tip having an outlet opening therein attached to said casing, and means between said inlet and tip having a series of restricted passages therethrough parallel to the axis of said casing and so disposed in said casing as to leave chambers adjacent the inlet to the casing and the outlet in the tip.
23. A head for a torch of the class described comprising the combination of a casing having openings therein including an inlet opening and a bottom opening, a tip having a central passageway therethrough and fitting the bottom opening, means for attaching the tip to the casing, and means having a contracted passageway therein between the inlet opening and bottom opening and leaving mixing chambers near the inlet opening and the passage way in the tip, for the purpose set forth.
24. In a torch of the class described, the combination of front and rear castings having passage-ways therein, pipes connecting said castings and the passage-ways therein, a mixing chamber in the front casting,

- nozzle discharging gas from one of said pipes into said mixing chamber, means for admitting gas from the other pipe to said chamber behind the outlet of said nozzle, a 5 burner head, a pipe connecting said mixing chamber and burner head, a tip mounted on the outlet end of the burner head, and means for controlling the flow of gas through said pipes to said mixing chamber.
- 10 25. A torch comprising a head having an inlet near one end, a substantially central outlet at the other end, and mixing chambers between said inlet and outlet, said mixing chambers being connected by a restricted passage-way extending longitudinally of the head, and the outlet of said passage-way being out of line with the outlet of said head, so as to resist back-fire.
- 15 26. In a torch of the class described, an oxygen supply pipe, an acetylene supply
- 20 pipe, valves for controlling the flow of gas through said pipes, said controlling valves having parts thereof disposed between said pipes, a device for operating said valves simultaneously, and means whereby said valves may be independently adjusted. 25
27. In a torch of the class described, the combination of an oxygen conducting means, an acetylene conducting means, valves for controlling the flow of gas through said 30 conducting means, means whereby said valves may be operated simultaneously and means whereby said valves may be independently adjusted.
- In testimony whereof I affix my signature 35
in presence of two witnesses.
